UNITED STATES PATENT OFFICE.

JULIUS L. WOLF, OF CINCINNATI, OHIO.

NOVELTY-DISPLAY FORM.

Application filed January 14, 1928. Serial No. 246,853.

This invention relates to novelty display forms and more particularly to forms for displaying neckware, handkerchiefs and other articles of wearing apparel and merchandise.

The object of my invention is to provide a simple, convenient, neat, attractive and economical form for use in boxes for displaying neckties, handkerchiefs and other articles of wearing apparel and merchandise.

Another object of this invention is to provide a series of small and inexpensive gifts, such as pencils, handkerchiefs, mouth-harps and the like, in conjunction with said display form, thereby giving an attractive appearance to the gift box and also giving a more realistic appearance to the illustration of the bust of an individual.

My invention consists in providing a gift box for individuals, and especially for boys, said box having a form with flanged edges whereby the body of said form is spaced apart from the bottom of the box and said form having on its outer surface an illustration of the bust of an individual, said form being provided with a cut-out portion and a plurality of exposed slits forming a part of the illustration and a plurality of concealed slots in said form for readily holding a four-in-hand necktie whereby it may be partly visible through said cut out and passed through one of said slits so that a large part of the tie will be exposed on the outer surface of the form and in this way graphically display the necktie substantially as it will appear when in actual use.

The invention also consists in the construction, combination, location and arrangement of parts, as herein fully set forth and claimed.

In the drawings:

Fig. 1 is a plan view of a novelty display form having a tie and handkerchief applied thereto and showing, by dotted lines, a gift attached thereto, such as a bullet pencil;

Fig. 2 is a longitudinal section of the parts shown in Fig. 1 and taken on a plane corresponding to line 2-2 of Fig. 1;

Fig. 3 is a plan view of the display form only before the edges are bent at right angles to its body and which clearly illustrates the cut-out used in connection with four-in-hand ties;

Fig. 4 is a similar view of the display form when used in connection with bow-ties;

Fig. 5 is a rear elevational view of Fig. 3

which more clearly shows the cut out slits and slots; and

Fig. 6 is a plan view of a novelty display form used in connection with bow ties, 60 which form is partly broken away for lack of space.

In the embodiment of my invention as illustrated and which shows a preferred construction I provide a novelty display form 65 1 having an illustration of the bust of a boy 2 on the surface thereof and provided with flanges 3, 4, 5 and 6, respectively, which flanges are adapted to be folded inwardly on dotted lines 7, thereby spacing the body 70 of said form 1 away from the bottom 8 of box 9. The illustration 2 of the bust of a boy includes shirt 10 having collar 11 and pockets 12 and 13. The top of imitation pockets 12 and 13, respectively, are cut 75 through, thereby forming slits 12^a and 13^a, respectively, as clearly shown in Fig. 5. When the form 1 is used for displaying four-in-hand neckties, I provide opening or cut-out 14 positioned adjacent the collar 11 and 80 inverted V-slit 15 in addition to slots 16 and 17 in flanges 3 and 5, respectively.

In assembling the gift package and when using a four-in-hand tie 18, as shown in Fig. 1, the first step is to fold the edges, 85 thereby forming flanges 3, 4, 5 and 6, respectively, inwardly upon dotted lines 7, thus forming support means for the body of the form 1 and concealing the slot 16 and 17. After the form 1 has thus been bent one end 90 of the folded necktie 18 is passed through slot 17 from the underside of said form and drawn over the outer surface thereof and then inserted through inverted V-slit 15, then through slot 16 whereupon the ends of 95 the tie are drawn toward each other thus giving said necktie the appearance of being tied in conjunction with the illustration of the bust of a boy designated as 2.

If the additional gifts are to be in the 100 form of pencil 19 and handkerchief 20 the corner of said handkerchief may be inserted through slit 13^a, from beneath the form, thus giving the effect of being worn in the imitation pocket 13. The clip 21 of pencil 19 may 105 be inserted through slit 12^a and in this way hold said pencil upon the form in plain view of the purchaser.

If it is desired to make up a gift box having a bow-tie 23 (in place of the four-in-hand tie 18) the form 1 is provided with 110 spaced apart cut-outs 22 whereby said bow-

tie may be graphically displayed on the outer surface of the form 1 adjacent the collar 11, as clearly shown in Fig. 6. 50

If it is desired to insert a different or 5 additional gift, such as a mouth harp, compass, memorandum book, etc., a suitable additional cut-out may be added in the form, such as cut-out 24 illustrated in Fig. 4, or 10 different in shape, as may be required to receive the said additional article.

Various other modifications may be made 15 in regard to the arrangement and placement of additional gifts but I wish to protect principally the manner in which the four-in-hand tie 18 and bow-tie 23 are displayed 20 on the outer surface of the form.

An advantage of this invention, in reference to the illustration of the four-in-hand tie 18 is that the tie, when so arranged, in 25 conjunction with the form 1, and after the form has been placed within box 9, the only portions of the tie visible to the eye of the observer is that portion of the tie appearing to the eye of the observer when actually 25 worn by a person.

Another advantage of this invention is 30 that the full size of a considerable portion of the tie 18 is displayed upon the surface of the form 1.

It will be understood that certain changes 35 and modifications of the invention can be made without departing from the scope or spirit thereof, as defined in the claims.

What I claim as new and desire to secure 40 by Letters Patent is:

1. A means for displaying neckwear comprising the combination of a box, a form bearing on its face an illustration of the bust of a person, flanges on the edges of 45 said form whereby the body thereof is spaced apart from the bottom of said box, a slot in the upper and lower flanges, a diamond shaped cut-out adjacent the collar of said illustration, a slit positioned beneath said cut-out, and a necktie adapted to be inserted in said slots and slit whereby it is partly visible through said cut-out and displayed upon the outer surface of the

form from the slit to the bottom of said form.

2. A means for displaying neckwear comprising the combination of a box, a form bearing on its face an illustration of the bust of a person, flanges on the edges of 55 said form whereby the body thereof is spaced apart from the bottom of said box, a slot in the upper and lower flanges, a cut-out adjacent the collar of said illustration, a slit positioned beneath said cut-out, and a necktie adapted to be inserted in said 60 slots and slit whereby it is partly visible through said cut-out and displayed upon the outer surface of the form from the slit to the bottom of said form.

3. A means for displaying wearing apparel comprising, in combination, a box, a form adapted to fit therein and be partly spaced apart from the bottom thereof, an illustration of the bust of a person on the face of said form, a concealed slot in the 70 upper and lower extremities of said form, a cut-out adjacent the collar of said illustration, a slit positioned beneath said cut-out, pockets forming part of said illustration, slits at the top of said pockets through 75 which wearing apparel such as handkerchiefs may be inserted from the rear of said form, and a necktie adapted to be inserted in said slots and passed through said slit from the back of said form to the front thereof whereby said tie is partly visible through said cut-out and displayed in actual 80 size from said slit to the bottom of said form.

4. A necktie display means comprising, in 85 combination, a box, a form having flanges on its side which are adapted to be bent at right angles to the face of said form and concealed in said box, a slot in two of said flanges, an opening located midway 90 said slots, a slit between said opening and one of said slots and an elongated slit on each side of said first-named slit, for the purposes specified.

JULIUS L. WOLF.
